UNITED STATES PATENT OFFICE

2,060,620

TRUCK

Henry Janssen, Wyomissing, Pa., assignor to
 Textile Machine Works, Wyomissing, Pa., a
 corporation of Pennsylvania

Application September 14, 1933, Serial No. 689,394

3 Claims. (Cl. 211—182)

My invention relates to hand trucks and particularly to hand trucks of the horizontal multiple shelf type each adapted for supporting and transporting a plurality of tray or rack units in relatively fixed relation to each other, and to the truck, in a manner permitting independent removal of any one of the trays from the truck without disturbing trays above, below, or at either side thereof.

Some of the objects of the invention are, to provide a truck of this type which is simple in construction, rugged, and particularly adapted to save time and facilitate the transportation and handling of yarn packages and racks therefor, in connection with the operation of braiding machinery.

With these and other objects in view, which will become apparent from the following detailed description of an illustrative embodiment of my invention shown in the accompanying drawings, the invention resides in a truck having therein the novel elements, features of construction and arrangement of parts in cooperative relationship as more particularly pointed out in the claims.

In the accompanying drawings:

Fig. 1 is a side elevation of the truck;

Fig. 2 is an enlarged sectional plan view taken on the line 2—2, Fig. 1;

Fig. 3 is a transverse section taken on the line 3—3, Fig. 1; and

Fig. 4 is a perspective view of a detail of the invention.

The truck, as illustrated in the drawings, is particularly adaptable for carrying yarn package, bobbin or spool racks or trays of the type disclosed in the applicant's United States Letters Patent No. 1,966,247 granted July 10, 1934, which comprises a substantially flat rectangular skeleton frame 1, provided with a plurality of rows of laterally spaced posts 2 adapted to enter center openings in yarn packages 3 for respectively supporting the yarn packages, spools, or bobbins 3, in vertical positions on the trays 1.

The truck comprises, in the present instance, a substantially rectangular horizontal base 10 in the form of an open framework including longitudinal side beams 11, 11 and transverse end beams 12, 12, preferably constructed of wood, which are secured together at the corners of the base 10.

Extending vertically from the four corners of the rectangular base 10 are upright shelf-supporting posts 13, 13 and 14, 14 respectively, of relatively heavy wood; and extending vertically from each of the side beams 11, 11, intermediate

the rear uprights 13 and the front uprights 14, are relatively thin metallic uprights 15 which are provided with footing elements 16 resting on and secured to the side beams 11, 11 respectively.

Secured to the inner transversely extending faces of each of the corresponding pairs of end uprights 13 and 14, and to the oppositely disposed transversely extending faces of the pair of intermediate uprights 15, is a series of transversely extending vertically spaced bars 17, 17, the vertical spacings of which are similar in each instance, and thereby positioning the bars 17 in horizontally aligned series, respectively disposed in vertically spaced horizontal planes.

Secured to each bar of each of the horizontally aligned series of transversely extending bars 17, 17, at each side of the truck, is a longitudinally extending bar 18, in the present instance in the form of an inverted channel bar having its web 19 secured to the under sides of the bars 17 and 20 its flanges 20, 20 projecting downwardly therefrom.

Secured to the longitudinal bars 18, 18, and extending transversely of the truck between the end and intermediate uprights 13, 15, 14, are transverse bars 21, 21, which, together with the bars 17, 17 and 18, 18 constitute a plurality of vertically spaced horizontal shelves 22, 22 each adapted to support a plurality of trays 1, 1.

The transverse bars 17 and 21 provide tracks or rails for supporting the trays 1, 1, the bars 17 each having a single horizontal flange or tray-supporting rail 17a. The intermediate bars 21 are each provided with a pair of horizontal tray-supporting flanges or rails 21a, 21a.

Extending vertically from the tray-supporting rails 17a of the bars 17, and from, and between the oppositely disposed tray-supporting rails 21a, 21a of each of the intermediate bars 21, are guide rails 17b and 21b respectively, which guide the trays into and out of the truck, transversely thereof, and which separate and hold the trays against relative movement with respect to each other and with respect to the truck longitudinally of the truck.

At the opposite ends of each of the cooperating tray-supporting rails 17a, 17b and 21a, 21b of the bars 17 and 21, respectively, are stop flanges or bumpers 17c and 21c, respectively, which extend transversely of the bars and prevent longitudinal movement of the trays 1 laterally of the truck.

As shown in Figs. 1 and 4, the guide rails 17b and 21b project above the top edges of the stops 17c and 21c for guiding the tray into the pockets 55

formed by the support, guide rails and bumpers within the area to be occupied by each of the trays.

By the above-described construction, each tray 5 is readily and independently removable from, and maintained in fixed position relative to, the truck.

The rear end of the truck is provided with supporting wheels 30, 30 inside the open frame-work of the base 10 adjacent to the side beams 11, 11 respectively, which are mounted on a transverse axle 31 carried by bearings or brackets 32 secured to the side beams 11, 11.

The truck is provided, at the front end, with 15 a pair of wheels 35, 35, mounted in castor frames 36, 36, which are swiveled in bearings 37, 37 secured to the base 10 in the angles between the side beams 11, 11 and end beams 12, 12 thereof, respectively.

20 The front end of the truck, in the present instance, is provided with a transversely extending handle bar 40 carried at its opposite ends in bearings 41, 41 secured to the uprights 14, 14 respectively.

25 Of course, the truck specifically shown and described can be changed and modified in various ways without departing from the invention herein disclosed and hereinafter claimed.

I claim:

30 1. In a rack adapted to support bobbin spindle trays of the type having a base providing with its end members, handle means within the confines of each of said trays at each end thereof, the combination of a series of shelves, four up- 35 rights mounted for mobility within which said shelves are built, said shelves comprising a plurality of longitudinally extending vertically spaced horizontal bars, a series of transversely extending horizontal cross bars mounted on said 40 longitudinal extending bars, said last named bars together providing pockets for the reception of bobbin trays, and undercut means at each end of the transversely extending bars facilitating initial guiding of bobbin trays to the pockets, 45 said transversely extending bars providing means

preventing lateral or longitudinal movement of the trays relative to the rack, upon the same being positioned in their respective pockets.

2. In a rack adapted to support bobbin spindle trays of the type having a base portion provided with openings adjacent its end members which facilitates grasping of the end members as handles, a series of shelves comprising a plurality of longitudinally extending vertically spaced horizontal bars, the combination with said shelves, of mobile mounting means therefor, means for initially and finally guiding and forming pockets for said bobbin spindle trays comprising cross bars adapted to be mounted in spaced relation on said longitudinally extending bars and provided with supporting means and guiding means positioned vertically with respect to said supporting means, end members located at each end of said bars and having a height less than the height of said guiding means thus 20 providing an additional initial guiding means for receiving said bobbin spindle trays.

3. In a rack adapted to support bobbin spindle trays and the like of the type having a base provided with openings adjacent its end members which facilitates grasping of the end members as handles, the combination of a series of shelves comprising a plurality of horizontally arranged inverted channel bars extending longitudinally of the rack, a plurality of uprights for supporting said shelves, a plurality of cross bars mounted on said longitudinally extending bars in such relation that their ends overhang at least some of the outermost longitudinally extending bars, thereby providing open spaces between said cross bars to facilitate grasping of the handles provided by the end members of the bobbin spindle trays, said cross bars also being provided with guide rails and end stops for said trays at both end of said rails of a height less 40 than said guide rails, for effecting initial guiding of the trays upon insertion thereof to the pockets formed by said cross bars.

HENRY JANSSEN. 45
